UNITED STATES PATENT OFFICE.

JOHN C. CROWSON, OF PENSACOLA, FLORIDA.

RAIL-CLAMP.

No. 922,394.

Specification of Letters Patent.

Patented May 18, 1909.

Application filed August 31, 1908. Serial No. 451,001.

To all whom it may concern:

Be it known that I, JOHN C. CROWSON, a citizen of the United States, residing at Pensacola, in the county of Escambia, State of Florida, have invented certain new and useful Improvements in Rail-Clamps; and I do hereby declare the following to be a full, clear, and exact description of the invention, such as will enable others skilled in the art 10 to which it appertains to make and use the same.

The present invention has relation to improvements in rail clamps, and it aims, primarily, to provide an extremely simple device of that nature which is arranged for attachment to a tie in such a manner as to be held positively against movement and consequent displacement, and which, when in place, will effectively prevent any spreading of the rail.

The invention further resides in the employment of specially formed bolts for attaching the clamp to the tie, and the provision of means for positively holding these 25 bolts against rotation.

With these objects in view, the invention briefly described, comprises a member formed with a seat arranged to receive the head or stem of the bolt by means of which it is secured to the tie, said seat being filled, after 30 the bolt is in place, with molten metal which on cooling, forms a seal around the head or stem of the bolt, and thus positively holds the latter against all movement.

The preferred embodiment of the invention 35 is illustrated in the accompanying drawings in which corresponding parts are designated by the same reference characters throughout the several views.

Of the said drawings, Figure 1 is a plan view of one form of the invention. Fig. 2 is a vertical section taken longitudinally on the line 2—2 of Fig. 1. Fig. 3 is a bottom plan view of one of the bolts employed. Fig. 45 4 is a top plan view of a slightly modified form of the bolt. Fig. 5 is a plan view of a second form of the invention. Fig. 6 is a longitudinal vertical section taken on the line 6—6 of Fig. 5. Fig. 7 is a horizontal 50 section taken on the line 7—7 of Fig. 6.

Referring to the drawings, and more particularly to Figs. 1, 2 and 3, 1 designates, generally, a flat topped solid metal tie of the ordinary type, and 2 one of the rails

which extend transversely across the tie and 55 are held in place by the clamps hereinafter described. As the clamps at both ends of the tie are identical, a description of one set will suffice.

As shown in Fig. 2, the right hand clamp 60 is in the form of a solid metal block 3 provided at its inner end with a projecting lip 4 which is arranged to extend across and rest directly against the adjacent flange of the rail. The lower portion of this block 65 fits in a seat 5 formed in the upper face of the tie, the end walls of the seat being inclined in the same direction. In the upper face of said block, there is formed a seat 6 which is rectangular in cross section, the 70 depth of the seat being approximately half the height of the block. This seat is arranged to receive the squared head of a bolt 7, whose threaded stem extends through registering openings formed in the block and in 75 the tie, as shown, the under face of the head of said bolt being arranged to contact with the bottom wall of the seat 6 when said bolt is tightened to the proper extent. The seat 6, above referred to, is filled, after the bolt 80 has been properly positioned and tightened, with molten lead or other suitable material 8, which when cooled, forms a seal. This seal surrounds the side and top faces of the bolt head, and thus positively prevents any 85 movement whatever of the bolt. The left hand rail flange is engaged by the head 9 of a bolt 10, whose threaded stem likewise extends through an opening formed in the tie, rotation of the bolt being effected by means 90 of a spanner or similar implement (not shown) with an upwardly extending squared shoulder 11 formed upon the convex upper face of the bolt head. The lower face of the bolt head is formed in like manner with a 95 depending neck 12 whose diameter slightly exceeds that of the stem of the bolt, the free lower face of said neck being brought into frictional engagement with the upper face of the tie when the bolt is tightened sufficiently. In the lower face of the bolt head is formed a series of inclined radial teeth 13. As above stated, the bolt head is arranged to engage at one side the left hand flange of the rail; at its remaining three 100 sides, said head is partially inclosed by a C-shaped member 14, which projects upwardly and is formed during the casting of

the tie. Into the partially inclosed box produced by this member, is poured a filling 15 of molten lead or other suitable material, the molten state of the filling permitting it to flow under and around the bolt head, so as to fill the interstices formed between the adjacent teeth 13. When the filling has hardened, it will be found impossible to rotate the bolt 10, the action of the filling being assisted by the formation of the teeth 13, some of which teeth will bite into the rail flange during the initial tightening of the bolt.

In Fig. 4, a slightly modified form of bolt head is shown, said head being generally designated by the numeral 9'. In this form of head, the teeth 13 are dispensed with, there being formed upon the upper face of the head a series of radial grooves or channels 13' into which the molten filling will flow and subsequently harden.

In the modified form of the invention illustrated in Figs. 5 to 8, the rail is clamped against the tie by means of a pair of counterpart metal blocks 3', each of which includes an integral lip 4' which is arranged to extend across and to be tightened against the adjacent flange of the rail. Each of these blocks is secured to the tie by means of a bolt 7' which extends through a vertical slot 6' formed in the block and through a bolt hole formed in the tie, that portion of the stem of each bolt which fits in the last mentioned opening being threaded. The slots 6', as shown in Fig. 7, are approximately elliptical in cross section, the length of their major axes being considerably greater than the diameter of the bolt stems, thus allowing a limited adjustment of the blocks with respect to the rail, prior to the tightening of the bolts.

The upper portion of the stem of the right hand bolt which fits in the corresponding slot 6' is rectangular in cross section, as shown in Figs. 6 and 7, and as designated by the numeral 16, while the corresponding portion of the left hand bolt is enlarged and is formed with a series of parallel notches 17, arranged longitudinally thereof. The squared portion and the notches in question are formed for the purpose of positively preventing any rotation of the bolts when the molten filling 8' has been poured into the slots 6' after the position of the blocks has been properly adjusted and the bolts then tightened. Each bolt terminates at its upper end in a square head 18, sufficiently large to extend at opposite sides beyond the corresponding edges of the slots, the under faces 60 of the heads being brought into contact with the upper faces of the blocks by the tightening of the bolts.

It will be apparent from the foregoing that in both forms of the invention, the 65 bolts, when once tightened, are positively

held against rotation by the seal formed by the cooled metal, and that this retention of the bolts holds the blocks against becoming loosened, so that the blocks exercise at all times their initial clamping pressure against 70 the rail flanges.

In the appended claims, the terms "seated member" and "member provided with a seat" are intended to refer to the blocks 3 and 3' as well as to the C-shaped member 14, the upward projection of the last mentioned member and the particular arrangement of the bolt head 9 with respect thereto being such that said head may be properly regarded as fitting in a seat.

What is claimed is:

1. The combination with a tie formed with a bolt hole, of a seated member provided upon the upper face of the tie; a bolt having the upper portion thereof disposed within the seat in said member, and the lower portion thereof fitting in the bolt hole; and a seal filling said seat and surrounding that portion of the bolt which is disposed therein.

2. The combination with a tie formed with a bolt hole, of a seated member provided upon the upper face of the tie; a bolt having the upper portion thereof disposed within the seat in said member, and the lower portion thereof fitting in the bolt hole; and a metal seal filling said seat and surrounding that portion of the bolt which is disposed therein.

3. The combination with a tie formed with a bolt hole, of a block mounted upon the upper face of the tie directly above the bolt hole, said block being formed with a seat and with a projecting lip; a bolt having its upper portion disposed in said seat, 105 and its lower portion fitting in said bolt hole; and a seal filling said seat and surrounding that portion of the bolt disposed therein.

4. The combination with a tie formed with a bolt hole, of a block mounted upon the upper face of the tie directly above the bolt hole, said block being formed with a seat and with a projecting lip; a bolt having its upper portion disposed in said seat, 115 and its lower portion fitting in said bolt hole; and a metal seal filling said seat and surrounding that portion of the bolt disposed therein.

5. The combination of a tie formed with 120 a bolt hole; a block mounted upon the upper face of the tie directly above the bolt hole and formed with a projecting lip and with a slot; a bolt having the upper portion thereof disposed within said slot, and the lower portion thereof fitting in the bolt hole; and a seal filling said slot and surrounding that portion of the bolt which is disposed therein.

6. The combination of a tie formed with 130

a bolt hole; a seated member provided upon the upper face of the tie directly above the bolt hole; a bolt having the upper portion thereof disposed within the seat in said member and its lower portion fitting in the bolt hole, the first mentioned portion of the bolt being formed with a series of notches; and a seal filling said seat and surrounding that portion of the bolt disposed therein, the seal entering said notches in said portion.

7. The combination of a tie formed with a bolt hole; a seated block mounted upon the upper face of the tie directly above the bolt hole; a bolt having the upper portion thereof disposed in the seat in the block, and its lower portion fitting in the bolt hole, the first mentioned portion of the bolt being formed with a series of notches; and a seal filling said seat and surrounding that portion

of the bolt disposed therein, the seal entering 20 said notches in said portion.

8. The combination of a tie formed with a bolt hole; a longitudinally-slotted block disposed directly above the bolt hole and formed with a projecting lip; a bolt having 25 the upper portion thereof disposed in said slot, and its lower portion fitting in the bolt hole the first mentioned portion of the bolt being formed with a series of notches; and a seal filling the slot and surrounding that 30 portion of the bolt disposed therein, the seal entering the notches in said portion.

In testimony whereof, I affix my signature, in presence of two witnesses.

JOHN C. CROWSON.
